CHARLES ELDON ROBINSON, OF WILLIAMSPORT, PENNSYLVANIA, ASSIGNOR TO E. KEELER COMPANY, OF WILLIAMSPORT, PENNSYLVANIA, A CORPORATION OF PENNSYLVANIA.

FURNACE-CLEANING DOOR.

1,289,917.

Specification of Letters Patent. Patented Dec. 31, 1918.

Application filed February 28, 1918. Serial No. 219,574.

To all whom it may concern:

Be it known that I, CHARLES ELDON ROBINSON, a citizen of the United States, and a resident of Williamsport, county of Lycoming, and State of Pennsylvania, have invented certain new and useful Improvements in Furnace-Cleaning Doors, of which the following is a specification.

My invention relates to a gravity actuated door closure of general application and specifically relates to such a type of door construction designed for sealing the clean out openings in water tube boilers.

In boiler practice it is desirable that a blow pipe or other cleaning apparatus be inserted from time to time into the boiler setting through the several clean out openings to blow off the soot and dust which accumulates about the water tubes. The boiler is usually hot, for the cleaning should take place daily and as cheap labor is employed for this purpose it is desirable to provide such a construction that the numerous doors can be pushed or quickly jerked into open position and restored into an air tight closed position without the necessity of the operator exercising any particular care in the operation.

Various attempts have been made to take air tight closing doors from other arts and adapt them to boiler work but the conditions incidental to their use in such high temperatured and dust accumulating constructions have not proven satisfactory. For instance, it has been proposed to guide the clean out doors in their movements to and from their open position by vertically inclined pin and groove guideway connections at opposite sides of the door openings. It has been found in practice that this type of door guide, even when carefully machined and positioned in place at great expense does not work smoothly after the grooves have been in use for awhile, for they become distorted by the heat conditions present and by warping of the masonry setting. Further, the guideways quickly become clogged with the furnace dust and even when care is taken to keep them free of dirt and dust, the frictional resistance to the door movement in dropping into place is almost sure to become greater on one side than on the other thus causing the door to cant to one side in falling and jam against

the side cheeks of the door frame or against

the groove in either case holding the door partially open thus giving rise to objectionable air leakage.

In order to close the door when so jammed the operator hammers the door into closed position and frequently breaks off one or both of the guide pins and otherwise damages the guiding means.

Even if this guiding groove and pin construction were entirely satisfactory in its operation the cost not only of the initial construction but also of the necessary repairs required due to the careless handling to which such devices are subjected, would make the use of such a refined construction almost prohibitive in boiler work.

Not only is it desired to secure the sealing of the door when dropped into closed position but it is also desired that the door, when moved into open position, shall remain in its fully opened position and shall be secured in this position against any accidental closing down on the cleaning apparatus.

Accordingly, the primary object of the invention is to provide a simple, inexpensive form of door closure for clean out furnace openings, which closure can be quickly and positively moved to a secured open position clear of any possible engagement with the cleaning apparatus and which will move automatically into an air tight closed position simply by pulling the closure away from its open position and allowing it to fall gravitationally.

The object is attained in general by utilizing the advantages of the vertically inclined guideway for moving the door laterally into closing position as it falls vertically but to eliminate the known grooved constructions and providing an open incline thereby avoiding the possibility of dust accumulations. Further the invention contemplates an engagement with this open incline which will provide a loose connection between the door and frame opening such as will permit the positioning of the door on top of the frame and which will be free of the incline until the door is approximately in position opposite its finally closed position.

Another object of the invention is to provide in such a construction, a door guiding and sealing means which can be ruggedly constructed at small cost, and with the use of a relatively small amount of material

105

110

but capable of withstanding the strains incidental to the careless use to which such doors are subjected.

A still further object of the invention is to 5 provide a construction which may be adapted readily to installation in conventional forms of clean out door openings and which can be readily replaced when damaged without materially re-organizing the door frames 10 now in general use and which at the same time will reinforce the door frame and door without adding material intentionally for this purpose.

Various other objects and advantages of 15 the invention will be in part obvious from an inspection of the accompanying drawings and in part will be more fully set forth in the following particular description of one form of mechanism embodying my invention 20, and the invention also consists in certain new and novel features of construction and combination of parts hereinafter set forth and claimed.

Referring to the accompanying drawings:—

Figure 1 is a perspective view and a portion of a furnace front including a clean out opening equipped with a preferred embodiment of my invention; 30 Fig. 2 is a vertical sectional view taken centrally of the device shown in Fig. 1 with the door shown in closed position in full lines and in an intermediate and open position in dotted lines; and also showing a detail of 35 construction slightly modified from the showing of Fig. 1;

Fig. 3 is a view in rear elevation and which may be considered as a rear view of the device shown either in Figs. 1 or 2.

In the accompanying drawing, there is 40 shown a conventional form of boiler front 10, provided with one of the clean-out openings 11 usually found in tubular boiler constructions. The opening is outlined by a forwardly projecting frame 12, which frame includes oppositely disposed side cheeks 13 and 14, a top plate 15 and a bottom plate 16 co-acting to form a box-like construction, the forward edge 17 of which is vertically disposed and constitutes a door abutting surface.

The opening is closed by means of a door 45 of any conventional form and provided on its rear side with a frame abutting surface 19 designed to fit flush against the abutting surface 17 to form an air-tight closure for the opening.

The top plate projects forwardly from the 50 boiler front with its upper surface flat and designed to provide a seat for the door when in the open position shown in Fig. 2. A projection 20 is positioned on the back side of the door adjacent its forward or lower edge and having a depth transversely of the plane 55 of the door at least equal to the thickness of

the top plate so that the projection can extend into the opening when the door is on its seat. The projection is disposed below the center of mass of the door so that the center of mass will be over the seat when the 70 door is in its open position, thus insuring the positive seating of the door on top of the frame and removed from any accidental displacement by the cleaning tool.

The inner side of the projection is defined 75 by a wedge member 21 of relative massive construction projecting laterally beyond opposite sides of the portion of the projection adjacent the door and having a relatively close fit between the side cheeks. 80 Opposite ends of the wedging projection are reduced and formed into small cylinders 22 and 23 constituting pivoting pins adapted when the door falls to engage rearwardly facing guiding surfaces 24 on guide members 85 25 defining opposite sides of the opening.

When the device disclosed constitutes an attachment for old clean out door construction these guide members may be simply 90 right triangular plates, as shown in Fig. 1, riveted to the inner sides of the cheeks with one edge 26 disposed flush with the surface 17. Where the entire construction is designed to include the illustrated form of 95 closure the plates are cast integrally with and form in effect a major portion of each of the cheeks. It may be considered that in the showing of Fig. 2 the side plates are formed integrally with the side cheeks. In either 100 case these members may be utilized to reinforce the side cheeks and to present additional abutting surfaces for the door. The guiding surfaces 24 are downwardly and rearwardly inclined, face into the interior of 105 the furnace and are free of any oppositely facing flange which might coat therewith to collect dust. As the pivoting pins engage the incline over a relatively short length thereof during the final closing movement 110 of the door, it is obvious that the guiding surface of the guide plates need have a length merely sufficient to engage the pins in all possible closing positions of the same, but in the device illustrated these plates are of 115 full depth of the interior of the frame to provide a deep bracing to the side cheeks.

In order to prevent the pins from moving forwardly out of the frame during the opening movement of the door, the upper portion 120 of the guide members are utilized as stops and to insure an easy swinging of the door into its fully opened position, rearwardly facing sockets 27 are formed in the upper portion of the guide surfaces. The front of 125 the door is provided with a curved lifting finger 28.

When the separate plates 26 are utilized, the door can be disposed in the fully opened position shown in dotted lines in Fig. 2 and 130

then the plates can be riveted in place. However, when the plates are cast integrally with the side cheeks it is necessary to provide means for permitting the mounting of the door. In one form of construction this is accompanied by recessing one of the cheeks to provide a horizontally disposed groove 29 having a depth sufficient to permit the insertion therein of the pin 23 and arranged 10 so that the pin could be moved rearwardly along the groove until the other pin 22 is positioned back of its guiding surface 24.

In operation and assuming that the door is in the closed position shown in Fig. 1, 15 the operator simply engages the door by the finger 28 and jerks the same upwardly. As the projection contacts with the underside of the top 15 the lower portion of the door is held thereby and the top portion falls 20 back on the seat provided by the top 15. At the same time the pins on the projection move forwardly and engage in the sockets thus insuring a square turning of the door about the axis of the pivot pins. When set 25 the lower portion of the door projects forwardly of the front edge of the top 15 which constitutes a turning edge for the door in its closing movement.

While in this open position even if the 30 cleaning tool should scrape against the downwardly extending projection the door will not be closed for it is held by the socket against forward movement and is held by the engagement of the projection against 35 the forward edge of the top 15 from any rearward movement. As this projection provides a long bearing against the top 15 the door is held approximately in position to insure a square turning of the door about 40 the forward edge of the top.

When it is desired to close the door the operator can pull the same forwardly by means of the cleaning tool until the door begins to drop. This will happen as soon 45 as the center of mass of the door is moved forwardly of the supporting seat. The operator need not give the door any further attention for it will drop automatically into closing position. During the first part of 50 the falling movement of the door the pins will be free of the inclined guiding surfaces so that the door can acquire considerable momentum to overcome any caked dust which may have accumulated in the path 55 of its final closing movement. Perhaps in falling one pin will be in advance of the other but this will in no way interfere with the actuation of the device for the forward pin will merely engage its surface permitting 60 the other pin to swing freely about the advance pin as a pivot and into engagement with its coacting surface. The momentum acquired by the falling door will cause the pins to snugly wedge against the guiding 65 surfaces thus forcing the door laterally of

its plane of falling movement and firmly against the bearing surface 17.

As the surfaces 24 are inclined almost perpendicularly the possibility of dust accumulating on these exposed surfaces is reduced to a minimum and even if dust did cake on the surfaces the pins are free to ride over any such formation. 70

The projection is purposely formed ruggedly so that the possibility of the pins 75 breaking off is practically eliminated. Further advantage is taken of this projection to brace the door across its rear face against warping. This projection tends to form a rigid door capable of withstanding the 80 strains imposed thereon incidental to the forcing of the edges of the door against the bearing surfaces of the frame.

As the engaging surfaces of the pin and 85 guiding surfaces wear away, the door does not lose its sealing efficiency for it merely drops down a little farther than originally and in order to insure this function the interengaging surfaces of the frame and door are initially constructed to give some 90 material length of bearing surface vertically.

Having thus described my invention, I claim:—

1. In a water tube boiler, a clean out door 95 construction including a supporting member, a box-like structure including side cheeks, and a top plate projecting forwardly from said supporting member to form a clean out opening, said cheeks provided with rearwardly exposed inclined guiding surfaces facing away from the front of the box-like structure, a closure for said opening provided with a projection on its inner side at least as deep as the thickness 100 of the top plate and a wedge engaging member defining the inner side of said projection and adapted to engage said guiding surfaces to move the door laterally as it falls by gravity. 110

2. In a water tube boiler, the combination of a door frame having a vertically extending front constituting a door abutting surface, guiding members at opposite sides of said frame and coacting to outline a part 115 of the door opening, said members each having a bearing surface inclined slightly from the vertical and facing rearwardly away from said door abutting surface, a door designed to contact with said abutting surface 120 to close the door opening, a wedging member bridged across the door opening, fixed to the rear side of the door and with opposite ends adapted to engage and slide down said bearing surfaces to draw the door laterally into firm closing contact with said abutting surface as the door falls gravitationally. 125

3. In a water tube boiler, a member provided with a clean out opening, a frame outlining said opening and including side 130

cheeks, and a top plate, triangular shaped plates engaging said cheeks to brace the same, said plates provided with guiding surfaces on their inner sides and exposed rearwardly to the interior of the boiler, a door for closing said opening and adapted to be moved into open position resting on and supported by said top plate, a wedge member fixed to and extending across the rear side of the door and adapted to slide down said inclined surfaces to draw the door laterally into closing engagement with the top plate as the door falls gravitationally.

4. In a device of the class described, the combination with a frame outlining an opening and providing a vertically disposed door abutting surface, the upper portion of said frame providing a door supporting seat, of a door having an open position supported on said seat and a closing position abutting said surface, and means for guiding the door in its final movement into its closing position.

5. In a device of the class described, the combination with a frame outlining an opening and providing a vertically disposed door abutting surface, the upper portion of said frame providing a door supporting seat, of a door having an open position supported on said seat and a closing position abutting said surface, a member having a guiding surface inclined downwardly away from said door abutting surface, said member having a socket at the upper end of said guiding surface, a pivot member fixed to the door and slidably down said guiding surface thereby to draw the door laterally into bearing engagement against said abutting surface and movable into said socket as the door is raised thereby to hold the pivot member as the door is lifted and thus cause the door to swing into position resting on said seat.

6. A furnace construction provided with a door opening frame including side cheeks and a top member constituting a door seat for the door when in open position, a door adapted when in substantially vertical position to close the opening, downwardly and rearwardly inclined guiding members positioned at opposite sides of the opening and exposed to the inside of the furnace, a wedge member spaced from said guiding members when the door is opened and adapted to fall into engagement with said members as the door moves into its final closing position.

7. In a device of the class described, a door adapted to fall vertically into closed position, a seat for supporting the door in open position and means operatively independent of the door during the initial part of its closing movement and coacting with the door in its final falling movement to move the same laterally into closed position.

8. In a device of the class described, a door adapted to fall vertically into closed

position, a seat for supporting the door in open position, means operatively independent of the door during the initial part of its closing movement and coacting with the door in its final falling movement to move the same laterally into closed position, said means including a vertically inclined guideway and a projection from the door spaced from the guideway when the door moves off its seat and said guideway disposed in the path of movement of the projection as it falls with the door.

9. In a water tube boiler, the combination of a frame provided with a vertically disposed door abutting surface, a door adapted to fit snugly against said surface, means providing a downwardly and rearwardly inclined guiding surface positioned within said frame and back of said abutting surface, a wedge member fixed to the rear side of the door and adapted to engage said inclined guiding surface to move the door laterally of its falling direction into engagement with said abutting surface, said wedge being free to move with the door vertically away from said inclined surface thereby to clear the surface as the door is lifted into open position.

10. In a water tube boiler, the combination of a frame provided with a vertically disposed door abutting surface, a door adapted to fit snugly against said surface, means providing a downwardly and rearwardly inclined guiding surface positioned within said frame and back of said abutting surface, a wedge member fixed to the rear side of the door and adapted to engage said inclined guiding surface to move the door laterally of its falling direction into engagement with said abutting surface, said wedge being free to move with the door vertically away from said inclined surface thereby to clear the surface as the door is lifted into open position and means for intercepting the rising movement of the wedge thereby to assist in a swinging of the door into open position.

11. In a water tube boiler, the combination of a frame provided with a vertically disposed door abutting surface, a door adapted to fit snugly against said surface, means providing a downwardly and rearwardly inclined guiding surface positioned within said frame and back of said abutting surface, a wedge member fixed to the rear side of the door and adapted to engage said inclined guiding surface to move the door laterally of its falling direction into engagement with said abutting surface, said wedging member extending across the door to brace the same against any distortion incidental to the forcing of the door against said abutting surface.

12. In a device of the class described, the combination with a member provided with a clean out opening, means providing a ver-

- tically disposed door abutting surface about said opening, a door for closing said opening, a support for the door when in open position, means for holding the door when 5 in open position loosely connected to said member, said last named means including mechanism for moving the door laterally of its falling direction when moved off its support and into engagement with said abutting 10 surface.
13. In a device of the class described, the combination of a door frame including side cheeks, side plates formed integrally with said cheeks, and each provided with a down- 15 wardly and rearwardly extending guiding surface, a door provided with a wedging member fitted between said cheeks and adapted to engage and slide down said guiding surfaces to move the door laterally into clos- 20 ing position against said frame.
14. In a device of the class described, the combination of a door frame including side cheeks, side plates formed integrally with said cheeks, and each provided with a down- 25 wardly and rearwardly extending guiding surface, one of said cheeks provided with a recess in rear of the guiding surface, a door provided with a wedging member fitted between said cheeks and adapted to engage and slide down said guiding surfaces to move 30 the door laterally into closing position against said frame, one end of said wedging member designed to be inserted in said recess so as to permit the other end to be disposed back of its coacting guiding surface 35 when the door is mounted in place.

Signed at Williamsport, in the county of Lycoming and State of Pennsylvania, this 14th day of February, A. D. 1918.

CHARLES ELDON ROBINSON.
